UNITED STATES PATENT OFFICE.

CLARENCE E. LOMAX, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed March 14, 1923. Serial No. 624,916.

The present invention relates in general to telephone systems, but more particularly to intercommunicating systems in which each station is provided with a plurality of keys, each key being capable of establishing a connection between the calling station and the station represented by the said key.

The principal object of the invention is to provide a new and improved common battery system of the above type in which secret service is assured.

Another object of the invention is the provision of a talking link so adapted that the operation of a single key will cause the calling end of this link to attach itself to the calling line, while the calling end of the said link will attach itself to the called line, thus completing the connection between the two stations.

These objects, together with others which will not be specifically pointed out now, will be more fully pointed out hereinafter, reference being had to the accompanying drawing which shows by means of the usual circuit diagrams sufficient of the apparatus employed in a system embodying the principles of the invention to enable the same to be understood.

Referring to the drawing, the stations #1 and #8 are ordinary telephone stations utilizing a direct current receiver and a common battery transmitter. When the switch hook is normal, the relays 9 and 10 are in bridge across their respective lines. When a station is called, direct current causes the associated relay to energize and open its own circuit, the relay therefore acting as a buzzer to signal the called subscriber.

The calling finder switch S and the called finder switch S' are located at a central point. The finder switches are of the rotary type in which the wipers move in a forward direction only. The switch S controls a set of wipers having access to banks B', B², and B³, while the switch S' controls a set of wipers having access to banks B⁴, B⁵, and B⁶. The positive and negative talking conductors from each substation in the system terminate upon contacts in the banks B² and B³, respectively. The contacts in bank B⁵ are multiplied with the contacts in bank B², while the contacts in bank B⁶ are multiplied with the contacts in bank B³.

A plurality of locking keys are provided

at each substation, there being one key for each telephone in the system. As shown in the figure, the key set K¹ is associated with substation #1. The key set K² is associated with the second station (not shown), while the key set K⁸ is associated with substation #8. It will be seen that there are no series connections, and that the multiplying of key sets may be carried on as desired.

The start conductor 15 is multiplied into every key in the system. There is also a calling multiple, such as the multiple 18, 19, or 20, which is local to each key set.

The calling multiple from a given key set is connected to that contact in bank B' which corresponds to the contacts in banks B² and B³, upon which the associated line conductors are terminated. There is a called multiple, such as the multiple 21, 22, or 23, for each substation in the system. The called multiple for a given station is looped into a key in each key set, and is connected to that contact in the bank B⁴ which corresponds to the contacts in banks B⁵ and B⁶ to which the associated line conductors are multiplied.

In general the operation of the system is as follows: When a subscriber desires to call a certain substation he operates the corresponding key of his key set. This operation starts the rotation of both switch S and switch S'. The calling switch S will seek for a grounded line, while the called switch S' will seek a line carrying battery potential. A further result of the operation of the aforementioned key is the grounding of the calling multiple through a resistance. A still further result of the operation of the aforementioned key is the connection of the called multiple with the calling multiple. As a result of the foregoing ground through a resistance will be placed upon a certain contact in the bank B⁴; this is without effect, however, as the switch S' is seeking battery potential.

When the wipers of the switch S reach the contact in bank B' which is associated with the grounded calling multiple the rotation will cease. A switching relay will now operate to place battery potential upon this contact; as the called multiple is connected to the calling multiple this battery potential now appears upon a certain contact in the bank B⁴. When the wipers of the switch S' reach the above mentioned contact in bank

B⁴ the rotation will cease, and a switching relay will operate.

When the calling switching relay operated, battery was placed upon the calling line, and as a result the relay at the calling substation operates to advise the calling subscriber that the connection has been completed. When the called switching relay operated battery was placed upon the called line, and as a result the relay at the called substation operates to signal the called subscriber. The first subscriber to remove his receiver will receive a ring back tone as an indication that the other party has not answered.

When the conversation is completed, the receivers are replaced, whereupon the relay at the calling substation will again operate as an indication that the operated key must be restored. When the key is restored the system returns to normal and is in readiness to complete another connection.

The system having been described in general, a detailed description will now be given 25 of its operation. For this purpose it will be assumed the subscriber at substation #1 desires to call substation #8. When key 8 of key set K¹ is operated a circuit is closed from ground, working contact and spring 30 24, starting conductor 15, conductor 25, resting contact and armature 26, armature 27 and resting contact, relay 28 to battery. A branch of the above circuit extends from grounded starting conductor 15, conductor 29, 35 resting contact and armature 30, armature 31 and its resting contact, relay 32 to battery. Relays 28 and 32 will energize and close the circuits of stepping magnets 33 and 34, respectively. Stepping magnet 33, upon energizing, will open the circuit of relay 28 at armature 27, thus the relay 28 and the stepping magnet 33 will operate alternately to advance the wipers of switch S step by step over the bank contacts. Stepping magnet 40 45 34 upon energizing, opens the circuit of relay 32 at armature 31; thus the relay 32 and the stepping magnet 34 will operate alternately to advance the wipers of switch S' step by step over the bank contacts.

50 A further result of the operation of key 8 in key set K¹ is the placing of ground upon the first contact in bank B' over a circuit traceable from ground, resistance R, spring 35 and its working contact, calling multiple 20 to the first contact in bank B'.

A still further result of the operation of the above mentioned key is the connection of the called multiple 21 with the calling multiple 20 at spring 36. At this time 55 ground through resistance R is placed upon the eighth contact in bank B⁴, but without effect.

When the wiper 17 engages the grounded contact in bank B' a circuit may be traced 60 from ground, resistance R, spring 35 and its

working contact, calling conductor 20, first contact in bank B', wiper 17, relay 37, to battery. Relay 37, upon energizing, stops the rotation of switch S by opening the circuit to relay 28 at armature 26. A further result of the energization of relay 37 is the placing of battery potential upon the eighth contact in bank B⁴. When the wiper 16 engages this contact a circuit may be traced from ground, relay 38, wiper 16, eighth contact in the bank B⁴, called multiple 21, spring 36 and its working contact, spring 35 and its working contact, calling multiple 20, first contact bank B', wiper 17, relay 37, to battery. From the foregoing it will be seen that relay 38 is now in multiple with resistance R. Relay 38, upon energizing, stops the rotation of switch S' by opening the circuit of relay 32 at armature 30.

A further result of the operation of relay 37 is the closure of a circuit traceable from ground, lower winding of relay 39, working contact and armature 40, wiper 12, first contact bank B³, positive line, normal switch hook contacts, relay 9, armature 53 and its resting contact, negative line, first contact bank B², wiper 11, armature 41 and its working contact, upper winding relay 39, to battery. The relay 9 will operate as a buzzer to indicate that the connection has been established.

A further result of the energization of relay 38 is the closure of a circuit traceable from ground, lower winding relay 50, working contact and armature 52, wiper 14, eighth contact bank B⁶, positive line, resting contact and armature 54, relay 10, normal switch hook springs, negative line, eighth contact bank B⁵, wiper 13, armature 51 and its working contact, upper winding relay 50 to battery. Relay 10 accordingly operates as a buzzer to signal the called party at station #8.

When the receivers are removed talking battery will be fed to stations #1 and #8 through impedance coils 39 and 50, respectively, and the conversation will proceed through the talking condensers 55 and 56. The first subscriber to remove his receiver will receive a ringback tone from the buzzer 105 at the other substation as an indication that the other party has not answered.

When the conversation is completed, the receiver will be restored and the relay 9 at the calling substation will operate as an indication that key 8 of key set K¹ must be restored. When key 8 is restored the circuit of relays 37 and 38 is opened, whereupon the said relays deenergize and the system returns to normal.

In further explanation let us assume that a connection has been established from station #1 to station #8. If at this time the subscriber at substation #2 desires to call substation #8 he will operate key 8 of key 130

set K², whereupon ground will be placed upon the second contact in the bank B'. The eighth contact of bank B⁴ is now connected through key 8 of key set K² to the second contact in bank B'. Additional ground has been placed upon start conductor 15, but without effect owing to the open contacts at armatures 26 and 30.

When the present conversation is completed the receivers will be restored, and key 8 of key set #1 will be restored to normal. The relays 37 and 38 will now deenergize and again close the grounded start conductor 15 through to relays 28 and 32, respectively, whereupon the switch S will advance its wipers into engagement with the second set of contacts in its bank, after which switch S' will come to rest with its wipers in engagement with the eighth set of contacts in its bank. The calling and called subscribers will now be signalled in the usual manner.

If it should happen that several calls are attempted during a busy period, the switches S and S' will establish new connection as soon as the old connection is released, the connections being established in the order in which the calling multiple appears in bank B'. There can be no wrong connections, as the switch S' does not switch through until switch S has determined the next connection to be established.

If it is desired that certain substations be given answering service only, no key sets need be provided at such substations.

35 The object and scope of the invention having been described, what is considered to be new and what it is desired to have protected by Letters Patent will be pointed out more fully in the appended claims.

40 I claim:

1. In a telephone system, a plurality of stations, a link circuit having an automatic switch at each end, lines for said stations multiplied in the banks of both of said switches, and means responsive to a call from one of said stations for causing one of said switches to automatically find the calling line and for causing the other switch to automatically find the called line.

50 2. In a telephone system, a plurality of stations, a link circuit having an automatic switch at each end, lines for said stations multiplied in the banks of both of said switches, means responsive to a call from one of said stations for starting an automatic hunting movement by both of said switches, and test circuits for causing one switch to stop on the calling line and the other switch on the called line.

60 3. In a telephone system, a plurality of stations, a link circuit having an automatic switch at each end, lines for said stations multiplied in the banks of both of said switches, means responsive to a call from one of said stations for starting an auto-

matic hunting movement by both of said switches, a test circuit for causing one switch to stop on the calling line, and another test circuit completed responsive to the finding of the calling line for causing the other switch to stop on the called line.

4. In a telephone system, a plurality of stations, a link circuit having an automatic switch at each end, lines for said stations multiplied in the banks of both of said switches, a test contact for each line in the bank of each switch, means responsive to a call from one of said stations for starting an automatic hunting movement by both of said switches and for placing a test potential on the test contact of the calling line in the bank of a first one of said switches, means for stopping such first switch controlled by such test potential, and circuit connections such that when the said first switch stops a test potential is placed upon the test contact of the called line in the bank of the other switch to stop such other switch.

5. In a telephone system, a plurality of stations, a link circuit having an automatic switch at each end, lines for said stations multiplied in the banks of both of said switches, means responsive to a call from one of said stations for starting an automatic hunting movement by both of said switches, a test relay for each switch, and a test circuit for energizing both relays in series to stop one switch on the calling line and the other switch on the called line.

6. In an intercommunicating telephone system, a plurality of stations, a set of keys at each station comprising a key for each of the other stations, automatic switching mechanism comprising two direct connected switches, lines for said stations multiplied in the banks of both of said switches, and circuit arrangements such that the actuation of a key at a calling station will cause one switch to connect with the calling line and the other switch to connect with the station corresponding to the actuated key.

7. In an intercommunicating telephone system, a plurality of stations, a set of keys at each station comprising a key for each of the other stations, automatic switching mechanism comprising two direct connected switches, lines for said stations multiplied in the banks of both of said switches, and circuit arrangements such that the actuation of any key will cause one switch to connect with the line of the station at which the key is located and will cause the other switch to connect with the line of the station which corresponds to the actuated key.

8. In an intercommunicating telephone system, a plurality of stations, a set of keys at each station, there being one key for each of the other stations, automatic switching mechanism responsive to the actuation of a key at any calling station to connect the

- calling line with the line of the station called, and circuit arrangements such that upon the restoration of the actuated key at the end of conversation said mechanism will operate automatically to connect the lines corresponding to any other key which may have been actuated before the conversation is finished.
9. In an intercommunicating telephone system, a plurality of stations, a set of keys at each station, there being one key for each of the other stations, automatic switching mechanism responsive to the actuation of a key at any calling station to connect the calling line with the line of the station called, circuit arrangements such that upon the restoration of the actuated key at the end of conversation said mechanism will operate automatically to connect the lines corresponding to any other key which may have been actuated before the conversation is finished, and means for automatically signalling the second calling party to notify him that his connection has been established.
10. In a telephone system, a plurality of stations, a link circuit having an automatic switch at each end, lines for said stations multiplied in the banks of both said switches, keys at each station corresponding to the other stations, and circuits closed by the actuation of a key at a calling station for causing one of said switches to connect with the calling line and for causing the other switch to connect with the called line.
11. In a telephone system, a plurality of lines, keys at the station on each line corresponding to the stations on the other lines, and two hunting switches responsive to the actuation of a key at a calling station to connect with the calling and called lines, respectively.
12. In a telephone system, a calling and a called line, a link circuit terminating at one end in a hunting switch having access to the calling line and at the other end in a hunting switch having access to the called line, and means at the calling station for causing said switches to start simultaneously and hunt for the calling and called lines, respectively.
13. In a telephone system, a calling and a called line, a link circuit terminating at one end in a hunting switch having access to the calling line and at the other end in a hunting switch having access to the called line, and means at the calling station for causing said switches to hunt simultaneously for the calling and called lines, respectively.
14. In a telephone system, a calling and a called line, a link circuit terminating at one end in a hunting switch having access to the calling line and at the other end in a hunting switch having access to the called line, means at the calling station for starting the hunting operation of said switches, means at the calling station for closing a test circuit for stopping the first switch on the calling line and for preparing a test circuit for stopping the second switch on the called line, and means in the first switch for closing said second test circuit.
15. In a telephone system, a link circuit for connecting a calling and a called line, an automatic switch at each end of said link circuit, each switch having a test wiper, a test relay in each switch, and circuits for both relays closed at the station on the calling line, each circuit including the test wiper of the associated switch.
16. In a telephone system, a link circuit for connecting a calling and a called line, an automatic switch at each end of said link circuit, a test relay in each switch, a circuit for one test relay including a wiper of its associated switch only, and a circuit for the other test relay including a wiper in both of said switches.
17. In a telephone system, a link circuit for connecting a calling and called line, an automatic switch at each end of said link circuit, an operating magnet in each switch for operating the same, a test relay in each switch for controlling its operating magnet, and a circuit including said relays in series.
18. In a telephone system, a link circuit for connecting a calling and a called line, an automatic switch at each end of said link circuit, a test relay in each switch, a circuit for the first test relay excluding the second, a circuit for the second test relay including the first, and a test wiper in the second switch included in the said second circuit.
19. In a telephone system, a plurality of lines, automatic selective switching mechanism for connecting with a calling one of said lines, other automatic selective switching mechanism for connecting with a called one of said lines, and a key at the station on the calling line for controlling the operation of all said switching mechanism.
20. In a telephone system, a plurality of lines, automatic selective switching mechanism for connecting with a calling one of said lines, other automatic selective switching mechanism for connecting with a called one of said lines, and means at the calling station for operating both switching mechanisms simultaneously.
21. In a telephone system, a plurality of lines, keys at the station on each line corresponding to the stations on the other lines, two hunting switches responsive to the actuation of a key at a calling station to connect with the calling and called lines, respectively, and means responsive to the calling party replacing his receiver without first restoring the actuated key for signalling the calling station.
22. In a telephone system, a plurality of stations, a link circuit having an automatic switch at each end, lines for said stations,

- and means responsive to a call from one of said stations for causing one of said switches to automatically find and signal the calling line and for causing the other switch to automatically find and signal the called line. 5
23. In a telephone system, a plurality of stations, a link circuit having an automatic switch at each end, lines for said stations, means responsive to a call from one of said 10 stations for causing one of said switches to automatically find and signal the calling line and for causing the other switch to automatically find and signal the called line, and means whereby the first party to answer 15 hears a tone induced by signalling current notifying him that the other party has not answered.
24. In a telephone system, a plurality of lines, a switch for finding the calling line, a second switch for finding the called line, 20 means for operating said switches, and means responsive to said first switch finding the calling line for subsequently stopping said second switch on the called line.
25. In a telephone system, a plurality of stations, a set of keys at each station, there being one key for each of the other stations, an automatic switching device responsive to 25 the actuation of a key at any calling station to connect the calling line with the line of 30 the called station, and means responsive to the calling party replacing his receiver without first restoring the actuated key for signalling the calling station.
26. In an intercommunicating telephone system, a plurality of stations, a set of keys at each station, there being one key for each of the other stations, automatic switching mechanism responsive to the actuation of a key at any calling station to connect the calling line with the line of the station called, 35 circuit arrangements such that upon the restoration of the actuated key at the end of conversation said mechanism will operate automatically to connect the lines corresponding to any other key which may have been actuated before the conversation is finished, and circuit arrangements such that if there is a plurality of keys actuated before 40 conversation is finished said mechanism will operate automatically to connect the lines in a predetermined order. 45

In witness whereof, I hereunto subscribe my name this 10th day of March, A. D. 1923.

CLARENCE E. LOMAX.
